UNITED STATES PATENT OFFICE.

WALTER W. MORU, OF KENOSHA, WISCONSIN.

DESIGN FOR A LAMP.

Application filed August 12, 1925. Serial No. 14,399. Term of patent 3½ years.

To all whom it may concern:

Be it known that I, WALTER W. MORU, a citizen of the United States, and a resident of the city of Kenosha, county of Kenosha, and State of Wisconsin, have invented a new, original, and ornamental Design for a Lamp, of which the following is a specification, reference being had to the accompanying drawing, forming part thereof.

The figure is an elevation of a lamp showing my new design.

I claim:

The ornamental design for a lamp as shown.

WALTER W. MORU.
